UNITED STATES PATENT OFFICE.

ALFRED BODE, OF BENRATH, NEAR DUSSELDORF, AND RICHARD BÜSING, OF BREMERHAVEN, GERMANY.

CRANE WITH REVOLVING JIB SLUING A COMPLETE CIRCLE.

No. 921,198.

Specification of Letters Patent.

Patented May 11, 1909.

Application filed February 2, 1907. Serial No. 355,524.

To all whom it may concern:

Be it known that we, ALFRED BODE, a subject of the German Emperor, and resident of Benrath, near Dusseldorf, in the Province of the Rhine, German Empire, and RICHARD BÜSING, a subject of the German Emperor, and resident of No. 6 Brgm. Smidt strasse, Bremerhaven, German Empire, have invented certain new and useful 5 Improvements in Cranes with Revolving Jib Sluing a Complete Circle, of which the following is an exact specification.

Our invention relates to so called tower-cranes or cranes of the hammer-type usually 15 employed at shipbuilding or general harbor work and consisting of an upright structure, which carries a horizontal jib extending in two directions, one side of the jib supporting the crab-runway, the other, the 20 balance weight.

According to the invention and in addition to the heavier crab running inside the jib-structure there will be another crab for lighter loads traveling the whole length of 25 both jibs. The structure of the crab extends to one side over the runway and far enough for the hook to pass the vertical center column of the crane. This allows of taking up loads on one side of the crane and 30 transferring them to the other side without sluing the jib. This is extremely important for shipbuilding work and unloading in general if the jib is situated between masts which make sluing difficult or even impossible. 35 The majority of such loads are not heavy and they may easily be brought to the other side without necessitating sluing of the crane, while heavy loads which must be lifted by the large crab and which would necessarily slue are certainly in the minority.

In the accompanying drawings Figures 1 and 2 give a side view of and a vertical section of the crane in form of a sketch. Fig. 3 shows a side-view of another arrangement. 45 Figs. 4 and 5 are respectively a side view and a vertical section of a further embodiment of the crane.

Inside of the longer side of the jib-structure there travels the main crab *b*. The 50 short side supports the balance weight in a manner already known. On top of the jib *a* travels auxiliary crab *c*. This crab (Fig. 2) carries the structure *d* which extends over

a and from which the hook *e* is suspended. Crab *c* travels from extremest position (Fig. 55 1) to the right over jib *a* up to the engine-house *f* and therefore can without sluing deposit any loads on the quay behind the crane, which have been taken from the vessel. If the engine-house is placed within the jib *a* (Fig. 3) it will be possible to extend the crab runway over both jibs *a* and *a'*.

The fixed extension *d* shown in Fig. 2 can be replaced by a revolving jib *g* or the like also traveling over both sides of the jib of the tower crane. 5

Having thus fully described the nature of our invention, what we desire to secure by Letters Patent of the United States is:

1. A tower crane with all-round sluing 70 jib characterized by a large crab (*b*) and a smaller crab (*c*) for lighter loads, the latter fitted with a jib extending over the structures *a* and *a'* and traveling on top of them in such a manner as to allow of transporting 75 loads from one side of the crane to the other without necessitating revolving of the tower crane.

2. A tower crane having a revolving jib extending to both sides of the tower and provided with a pair of crab-runways; one of 80 said runways extending solely to one side of the tower and the other runway extending to both sides of the tower.

3. A tower crane having a revolving jib 85 extending to both sides of the tower and provided with a pair of crab-runways; one of said runways being located within the jib and the other runway being located on the top of the jib and extending to both sides of 90 the tower.

4. A tower crane having a revolving jib extending to both sides of the tower, a main crab adapted to travel on the part of the jib to one side of the tower, and an auxiliary 95 crab adapted to travel on the parts of the jib to both sides of the tower.

5. A tower crane having a revolving jib extending to both sides of the tower, a main crab adapted to travel on the part of the jib 100 to one side of the tower, and an auxiliary crab adapted to travel on the parts of the jib to both sides of the tower; said last named crab having a jib extending laterally beyond said first-named jib. 105

6. A tower crane having a revolving jib

extending to both sides of the tower, a main crab adapted to travel on the part of the jib to one side of the tower, and an auxiliary crab adapted to travel on the parts of the jib 5 to both sides of the tower; said last-named crab having a revoluble jib extending laterally beyond said first-named jib.

The foregoing specification signed at Dus-

seldorf, Germany this seventeenth day of January, 1907.

ALFRED BODE.
RICHARD BÜSING.

In presence of two witnesses—
M. ENGELS,
ALFRED POHLMAYER.
